GARBAGE FILL

John P. Holland, San Francisco, Calif.

Application July 3, 1934, Serial No. 733,587

4 Claims. (Cl. 61—35)

This invention relates to the problems of reclaiming waste land and simultaneously disposing of city refuse or garbage.

One object of this invention is to provide a compact, firm, fill for mud flats, marshes, and low lands, utilizing for that purpose very little materials other than ordinary garbage. A further object is to accomplish in connection with the filling in of low lands, the disposing of city refuse or garbage in a sanitary manner.

I find that ordinary garbage or city refuse, because of its large content of paper materials, will, when treated in the manner hereinafter set forth, provide a substantial, solid, firm fill suitable for building-sites, roadways, parks, etc., without the necessity of utilizing any appreciable amount of earth.

My method consists of dumping the garbage collected from municipalities, which ordinarily contains in excess of fifty per cent, paper material, in a layer say of three or four feet in depth, then thoroughly soaking the layer with water until the paper content becomes more or less pulp-like, then thoroughly compacting the layer, preferably with a roller, exerting a pressure of some ten to fifteen tons, until the layer is reduced in thickness to about one-half of its original thickness. For the purpose of compressing the layer, I prefer to employ a spiked roller, so as to break up the larger pieces contained in the garbage and which might tend to form bridges and leave voids. After compressing the layer, I apply a deposit of a thick, viscous oil, preferably an asphaltic oil or emulsion. The oil should be in heated condition, so that it will flow readily and spread and enter any crevices and depressions in the layer, and the quantity applied should be sufficient to form a coating throughout the top of the layer of compressed garbage. The oil serves as a binder and a top dressing for the compacted layer and at the same time it kills any objectionable odors emanating from the garbage, and repels rats.

Successive layers of garbage and oil are applied in like manner, until the desired level is reached. Even without the addition of any earth, or at least any appreciable quantity, such a filling is sufficiently firm to serve all the ordinary purposes of solid earth.

On the accompanying drawing I have illustrated how the garbage fill is applied to a mud flat 10. Several layers of water-soaked, compressed garbage are indicated at 11, 12 and 13. The oil layers are indicated at 14, and the parts below these oil layers indicated at 15 are formed by the entrance of the oil into the depressions left by the spiked roller. Thus the capability of the oil to serve as a binder is facilitated.

In and by my method, valuable land adjacent large cities, which otherwise would be not only waste land but a nuisance, can be created, utilizing principally the refuse or garbage from the city. The garbage disposal problem is thereby solved in a manner which is entirely sanitary and profitable.

While I have described various details of my invention, yet I have done so by way of illustration and not as a limitation thereof, since changes may be made without departing from the spirit of the invention the scope of which is defined in the appended claims.

Having described my invention, what I claim and desire to secure by Letters Patent is:

1. A method of filling low lands which consists of dumping a layer of garbage containing a large percentage of paper material, soaking the layer with water, compressing the layer to about one-half of its original thickness, applying a coating of heavy, viscous oil to the compressed layer, so as to penetrate the layer and leave a coating thereon top, and proceeding in the same manner with other layers until the desired level is attained.

2. The method of filling in mud flats and the like and disposing of municipal refuse containing a large proportion of paper material, which comprises providing on said mud flats a layer of said refuse soaked with water, compressing said layer to about one-half its thickness, covering said resulting compressed layer with a hardening oil, and repeating said series of steps a sufficient number of times to produce the desired depth of fill.

3. The method of filling in mud flats and the like and disposing of municipal refuse containing a large proportion of paper material, which comprises providing on said mud flats a substantially four-foot-thick layer of said refuse soaked with salt water, rolling said four-foot thick layer with a twelve-ton roller to a thickness of about two feet, and covering said resulting layer with hot asphaltic oil, said steps being repeated the number of times necessary to make the desired thickness of fill.

4. The method of filling in mud flats and the like and disposing of municipal refuse containing a large proportion of paper material, which comprises providing on said mud flats a layer of said refuse soaked with water, simultaneously indenting and compacting said layer to about one-half its thickness, and filling the resulting indentations and covering said resulting layer with a hardening oil, said steps being repeated the number of times necessary to make the desired thickness of fill.

JOHN P. HOLLAND.
